UNITED STATES PATENT OFFICE.

OTTO W. FELDMAN, OF ST. LOUIS, MISSOURI.

COMBINATION FAUCET AND DRINKING FOUNTAIN.

Application filed May 31, 1919. Serial No. 300,810.

To all whom it may concern:

Be it known that I, OTTO W. FELDMAN, a citizen of the United States, and resident of the city of St. Louis, State of Missouri, have invented certain new and useful Improvements in a Combination Faucet and Drinking Fountain, of which the following is a specification.

This invention relates to improvements in a combination faucet and drinking fountain, and has for its object a spigot having two discharge or outlet openings, and a valve for controlling the same.

A further object of my invention is to construct a faucet which can be used for delivering water in the usual manner as well as providing a drinking or bubble fountain, either one of the discharges being operated by the same valve.

20 The essential feature of my invention is to provide a means whereby a faucet can be used for two purposes and operated by the same valve.

Figure 1, is a vertical sectional view of my invention.

Figure 2, is a horizontal sectional view of the same.

Figure 3, is a side view of my invention.

30 Figure 4, is a detail perspective view of the excentric made use of for operating the water control valve.

Figure 5, is a detail sectional view of the valve portion of the faucet showing the position of the valve for opening the bubble fountain.

Figure 6, is a similar view to Figure 5 but showing the faucet portion open.

In the general construction of my invention I provide a body portion 7 comprising 40 a tubular section 8 its outer free end having screw threads 9 for engagement with the pipe connection of the plumbing system.

The mouth of the tubular section 8 is in the form of a valve seat 10 in which rests 45 and is seated the usual fuller ball 11 which is secured to a stem 12 extending into the tubular section and its opposite end fastened to an arm 13 of an excentric 14.

On the body portion 7 is an upper extension 15 which comprises a drinking or bubble fountain 16, its upper end is provided with a sieve or perforated disc 17 which is held in position by the cap 18 of non corrodible material.

55 The front end of the faucet is provided with the usual discharge nozzle 19, both

the nozzle and fountain are provided with passages 20 and 21, and the opening and closing of the same is controlled by the cylinder valve core 22, this valve core is in 60 the form of a hollow cylinder which has an opening at the point indicated by the numeral 23, the end 24 is provided with a pin 25 which fits in the aperture 26 formed in the excentric 14, this pin is set to one 65 side so that when the valve is turned in either direction the excentric will move back pushing on the rod or stem 12 freeing the fuller ball 11 from the seat 10 thereby permitting the water to enter the faucet.

The opposite end of the cylinder valve is provided with a trunnion 27 to which is fastened a handle 28 by which the valve is turned. The valve is held in the casing 70 with leakproof connection by the cap 29.

In order to operate the bubble fountain, the valve handle 28 is moved down turning the valve core to the position as shown in Figure 5, and to open the nozzle 19 the handle is turned up, which places the valve 80 in the position as shown in Figure 6.

In either case when one is open the other is closed, this is accomplished by the solid portion of the valve core, the hollowness of the valve is to permit the water to enter 85 thereby enabling its pressure to keep the valve in close contact with the bore in which it is seated.

By this structure of faucet, an ordinary hydrant can be equipped with a faucet 90 which can be utilized for both water distribution, and a sanitary drinking or bubble fountain.

Having fully described my invention what I claim is:

1. A faucet of the character described comprising a body portion, a cylindrical hollow valve located horizontally in said body portion, that portion of the body in which the valve is located being of wider 100 diameter than the remaining portion, an integral vertical hollow extension located above the wider portion of the body, a perforated cap placed over the same, said extension and cap constituting a bubble fountain, said extension communicating with the interior of the cylindrical valve in one position of the latter and a nozzle extending on the fore end of the body portion and communicating with the interior of the 110 cylindrical valve in a second position thereof, an eccentric connected with the end of

- the valve, means for controlling the admission of water into the body portion and means connecting said eccentric and said controlling means, substantially as specified.
- 5 2. A combined faucet and drinking fountain comprising a casting consisting of a hollow body portion, a nozzle and a drinking fountain all cast integral, the fountain being arranged vertical and at right angles to the body portion, an elongated hollow cylindrical valve located in the casting and controlling the ports of the fountain and nozzle, a portion of the wall of the valve being cut away to form an opening to correspond with the ports of the nozzle and

fountain, a pin projecting on the end of the valve, an eccentric located on the pin, a rod connected to the free arm of the eccentric and an admission valve located on the rod by which water is admitted into the casting 20 by the movement of the cylindrical valve, substantially as specified.

In testimony whereof, I have signed my name to this specification, in presence of two subscribing witnesses.

OTTO W. FELDMAN.
